MULTIPLE CYLINDER PUMP

Paul C. Temple, Decatur, Ill., assignor to A. W. Cash Company, Decatur, Ill., a corporation of Delaware

Application October 9, 1942, Serial No. 461,399

8 Claims.

(Cl. 103—5)

This invention relates to hydraulic transmissions, and more particularly to a multiple cylinder pump or sender capable of furnishing pressure fluid at a desired rate for the operation of a motor or receiver.

Mechanisms of this general type are ordinarily driven at a constant speed in one direction, provision being made to vary the pump displacement and to reverse the direction of the fluid flow, so that the speed and direction of rotation of the motor can be controlled. It is also customary to supply make-up fluid to the inlet of the pump at a sufficiently high pressure to avoid cavitation and insure complete filling of the pump cylinders at each stroke. Since the pump inlet becomes the outlet when the flow is reversed, such reversal necessitates a delivery of the make-up fluid in a different path of flow. It is also important to avoid any overloading of the various parts by reason of excessive fluid pressure at the pump outlet, regardless of the direction of flow. With certain prior constructions, adjustment of the displacement has required a considerable manual effort on the part of the operator.

It is one object of the invention to provide a multiple cylinder pump of the variable displacement type which will be highly efficient in operation, and comparatively free from friction and wear.

It is a further object of the invention to provide a multiple cylinder pump of the variable displacement type which will be comparatively simple and inexpensive to manufacture and thoroughly dependable in service.

It is a further object of the invention to provide a multiple cylinder pump of the reversible flow type having a simple and dependable means of supplying make-up fluid automatically to the inlet of the pump regardless of the direction of flow.

It is a further object of the invention to provide a multiple cylinder pump of the reversible flow type having simple and dependable means for relieving excess fluid pressure from the outlet side of the pump regardless of the direction of flow.

It is a further object of the invention to provide a multiple cylinder pump having a simple and dependable means for adjusting the pump displacement quickly and accurately, the said adjustment requiring only a slight manual effort on the part of the operator.

With these and other objects in view, as will be apparent to those skilled in the art, the inven-

tion resides in the combination of parts set forth in the specification and covered by the claims appended hereto.

Referring to the drawings illustrating one embodiment of the invention, and in which like reference numerals indicate like parts,

Fig. 1 is a sectional plan view of the pump or sender of a hydraulic transmission, the section being taken on the line 1—1 of Fig. 2;

Fig. 2 is a view of the pump partially in front elevation and partially in section taken on the line 2—2 of Fig. 1;

Fig. 3 is a section taken substantially on the line 3—3 of Fig. 2;

Fig. 4 is a section taken on the line 4—4 of Fig. 1;

Fig. 5 is a section taken on the line 5—5 of Fig. 1;

Fig. 6 is a section taken on the line 6—6 of Fig. 2;

Fig. 7 is a section taken on the line 7—7 of Fig. 1;

Fig. 8 is a fragmentary view of the pump partially in rear elevation and partially in section taken on the line 8—8 of Fig. 6;

Fig. 9 is a fragmentary view taken on the line 9—9 of Fig. 8;

Fig. 10 is a section taken on the line 10—10 of Fig. 3;

Fig. 11 is a front elevation of the pump and its associated supporting base, the base being partially broken away for clearness of illustration; and

Fig. 12 is a plan view of the apparatus.

The embodiment illustrated comprises a casing 15 which is mounted upon a hollow base 16 (Fig. 11), this base forming a reservoir for oil. Within the casing, and as best shown in Fig. 1, there is provided a main rotor 17, which is supported by a pair of axially spaced ball bearings 19 and 20. This rotor is provided with a shaft 21 which extends outwardly from the casing for connection with a suitable source of power. An auxiliary rotor 22 is mounted within the casing in spaced relation with the main rotor, this auxiliary rotor being supported by a pair of axially spaced ball bearings 23 and 24 carried by a member 25. As shown in Fig. 2, this member 25 is in the form of a yoke which is pivotally supported by a pair of aligned pins or trunnions 26 mounted on the casing walls. The axes of the two rotors are in a common horizontal plane, and the trunnions 26 are positioned in a vertical line which passes through both of these axes.

In the drawings the yoke 25 is shown in its cen-

tral or neutral position, with the axes of the rotors aligned. By swinging the yoke in either direction about its trunnions, the axis of the auxiliary rotor will be made to intersect the axis of the main rotor at an obtuse angle.

The two rotors are connected so that they will rotate simultaneously and in the same direction. For this purpose a coupling spindle 28 is provided between the rotors, and its opposite ends are connected to the respective rotors by means of universal joints. In the preferred construction illustrated each of these joints comprises a ring 29 which is pivotally connected to the corresponding rotor by means of two aligned pins 30 and to the adjacent end of the spindle by means of two similar aligned pins 31 spaced ninety degrees from the pins 30. The two pins 31 at one end of the spindle are located in a common plane with the two pins 31 at the opposite end of the spindle, so that the two universal joints are in the same phase. Furthermore the line of centers of the trunnions 26 is equidistant from both universal joints, so that the axis of the spindle will always intersect the axes of the two rotors at equal angles. With this construction the angular velocities of the two rotors will always be equal. In order to facilitate assembly and permit the change of length required by adjustment of the yoke, the spindle 28 is formed of two telescoping parts connected by multiple splines.

A series of fifteen expandable and contractible fluid displacement units is arranged in a circle around the coupling spindle 28. Each of these units preferably includes two telescoping parts in the form of a cylinder 33 and a piston 34 slideable therein. The opposite ends of each displacement unit are connected to the adjacent rotors 17 and 22 by swivel joints, preferably of the ball-and-socket type. As illustrated the rotor 17 is provided with a circular series of spherical members 35 which fit within similarly shaped sockets 36 in the adjacent ends of the cylinders 33, and the rotor 22 is provided with a circular series of spherical members 37 which fit within similarly shaped sockets 38 in the adjacent ends of the pistons 34. With this construction, and the yoke adjusted to either side of its neutral position, the pistons will make one complete stroke in each direction for every revolution of the rotors. The axis of each cylinder-piston unit will always be in a direct line connecting the centers of the corresponding spheres 35 and 37, and there will accordingly be no side thrust or cramping forces involved between the pistons and their respective cylinders. It is therefore feasible to provide much greater angular adjustment for the yoke than would otherwise be the case, thus increasing the piston stroke and the capacity of the pump for a given size and weight. To facilitate assembly, the sockets 36 are in part formed in collars 39 attached by screw threads to the ends of the cylinders, and the sockets 38 are in part formed in collars 40 attached by screw threads to the ends of the pistons. The spherical members 35 are provided with screw threaded shanks 42 secured in the rotor 17, and the spherical members 37 are provided with tapered shanks 43 which are secured to the rotor 22 by means of nuts 44.

Provision is made for the admission and discharge of fluid to and from the cylinders 33 in proper synchronism with the movements of the various parts. For this purpose each of the spherical members 35 is provided with a central bore 46 which extends through the shank 42 and

communicates with a duct or passage 47 formed in the rotor 17. Each of the passages 47 leads to a port 48 which opens radially outward in a cylindrical portion of the rotor between the ball bearings 19 and 20. This portion of the rotor fits rather closely within a cylindrical bore 49 in the casing 15. The bore 49 is provided with two diametrically opposed circumferentially extending grooves or chambers 51 and 52 located in line with the ports 48 and arranged to be connected with external pipes 53 and 54 respectively. These pipes may lead to a suitable hydraulic motor (not shown). The chambers are separated by two diametrically opposed abutments 55 and 56 (Fig. 3) which lie in the horizontal axial plane. The width of these abutments, measured circumferentially, slightly exceeds the circumferential width of the ports 48, so that the ports will communicate with the chambers 51 and 52 alternately, but no port will communicate with both chambers simultaneously. For convenience in manufacture, the rotor 17 is formed of two flanged pieces which are fastened together by four pins 57 (Fig. 3). The passages 47 can be readily obtained by drilling, the unwanted openings being plugged as shown in Fig. 1.

The cylinders and pistons are so constructed as to substantially eliminate all friction and wear from the ball-and-socket joints. This is accomplished by exposing each of the joints to the fluid pressure within the corresponding cylinder, over a projected area substantially equal to and preferably very slightly less than the effective area of the piston. For this purpose each piston 34 is provided with a passage 59 (Fig. 1) which extends centrally therethrough so that fluid from the cylinder will be admitted into direct contact with the spherical member 37. At the end adjacent the member 37 this passage 59 is formed with a counterbore or enlargement 60 having a diameter slightly less than the diameter of the piston. In addition, the bore of each cylinder 33 is slightly contracted at 61, adjacent the spherical member 35, to a diameter slightly less than that of the piston. With this construction there will be only a very slight axial thrust on each cylinder and piston, caused by the fluid pressure on the very small area represented by the difference in area between a circle having a diameter equal to that of the piston and a circle having a diameter equal to that of the enlargement 60 or the contracted portion 61. This slight thrust is desirable since it minimizes leakage of fluid past the ball-and-socket joints without imposing any appreciable friction load thereon. In practical effect this construction applies the fluid pressure directly to portions of the rotors, i. e., the spherical members, rather than indirectly through the medium of the cylinders and pistons.

These latter parts are used simply to confine the fluid and not to transmit heavy mechanical forces to or from the fluid as in prior mechanisms.

Means is preferably provided to supply make-up fluid to the inlet of the pump at an appreciable pressure in order to ensure complete filling of the cylinders at each stroke. For this purpose I have shown a geared rotary pump 63 comprising a driving gear 64 (Fig. 8) keyed to the shaft 21 and a driven gear 65 rotatably mounted on a stud 66 and meshing with the gear 64. These two gears cooperate in known manner to transfer fluid from an inlet chamber 68 (Fig. 6) to an outlet chamber 69. Between these two chambers there is provided a port 70 controlled by a relief

valve 71 loaded by a helical compression spring 72. With this construction a substantially constant fluid pressure will be maintained in the chamber 68, any excess fluid being returned to the chamber 68 through the port 70. Fluid is delivered to the inlet chamber 68 from the reservoir 16 through a pipe 73 having an inlet screen 74, and fluid travels from the outlet chamber 68 through a pipe 75 to a distributing valve mechanism 76.

As best shown in Figs. 3 and 5, the valve mechanism 76 is arranged to deliver the fluid from the pipe 75 automatically to the inlet side of the main pump, regardless of the direction of flow as determined by the adjustment of the yoke 25. For this purpose the mechanism 76 is shaped to provide an upper chamber 78 which is connected with the chamber 51 by a passage 79, a lower chamber 80 which is connected with the chamber 52 by a passage 81, and an intermediate chamber 82 which receives fluid directly from the pipe 75. A check valve 84 is provided between the intermediate chamber 82 and the upper chamber 78, and a second check valve 85 is provided between the intermediate chamber and the lower chamber 80. Both of these check valves are arranged to open in the direction of flow out of the intermediate chamber, and they are preferably urged toward their closed positions by light helical compression springs 86. Preferably the two check valves are axially aligned and provided with stems 87 which extend toward one another in abutting relation and of such lengths that when one valve is closed the other valve will be held open. Two pressure relief valves 89 and 90 are provided between the upper and lower chambers 78 and 80, these valves being urged toward their seats by heavy helical compression springs 91. The valve 89 opens in the direction of flow out of the upper chamber 78, and the valve 90 opens in the direction of flow out of the lower chamber 80. If the pressure in either of the chambers 51 or 52 tends to become excessive, one or the other of the valves 89 and 90 will open automatically to allow fluid to flow directly from the high pressure side of the main pump to the low pressure side thereof. It will be apparent that one of the check valves 84 and 85 will be held closed by the pressure at the discharge side of the main pump, the other check valve being open to allow flow of make-up fluid from the geared pump 63 to the inlet side of the main pump.

The yoke 25 can be moved about its trunnions 26, to control the volume and direction of the fluid flow through the main pump, by a hydraulically actuated mechanism, which in the embodiment illustrated is controlled manually. For this purpose, as shown in Fig. 4, two horizontal cylinders 93 are mounted one above the other on one side of the casing 15, and two horizontal cylinders 94 are mounted one above the other on the other side of the casing. The inner ends of these cylinders open into the casing. A single-acting piston 95 is slidably mounted within each of the cylinders 93, and a single-acting piston 96 is mounted within each of the cylinders 94. Each of the four pistons is joined by a connecting rod 97 to the yoke 25. By admitting fluid to the cylinders 93, the yoke can be swung in one direction, and by admitting fluid to the cylinders 94 the yoke can be swung in the opposite direction.

The admission and discharge of fluid from the cylinders 93 and 94 are controlled by a four-way pilot valve mechanism including a casing 99 (Figs. 3 and 10) shaped to provide two spaced chambers

100 and 101 which I shall refer to as a "forward" chamber and a "reverse" chamber respectively. Between these two chambers there is provided an inlet chamber 102 which is supplied with pressure fluid through a pipe 104 connected with the pipe 75. The "forward" chamber 100 is connected with the two cylinders 93 by a pipe 105, and the "reverse" chamber 101 is connected with the two cylinders 94 by a pipe 106. A cylindrical sleeve 107 is mounted in the casing 99 and provided with radially extending ports which connect with the three chambers, the ends of the sleeve being open to the casing. Within this sleeve there is mounted a slideable pilot valve 108 having axially spaced cylindrical enlarged portions 110 and 111 which normally close the ports leading to the chambers 100 and 101 respectively. The pilot valve is so constructed that when it is moved in either direction from the neutral position illustrated, it will admit pressure fluid from the pipe 104 to one of the chambers 100 or 101 while allowing fluid to exhaust from the other chamber into the main pump casing 15, whence the fluid will return through a drain pipe 112 (Fig. 11) to the reservoir 16.

The pilot valve mechanism illustrated is arranged for manual control, and for this purpose there is provided a hand lever 114 (Fig. 10) which is secured to the upper end of a vertical shaft 115 rotatably supported in the casing 99. This hand lever is provided with a pointer 116 which travels over a scale 117 to indicate the position of adjustment. A lever arm 119 is secured to the lower end of the shaft 115, this arm being connected by a link 120 to one end of a floating lever 121. The other end of the lever 121 is connected to the pilot valve 108. The lever 121 is fulcrumed intermediate its length on one end of a link 123 which is connected at its other end to a lever 124 (Fig. 2), the lever 124 being fulcrumed intermediate its length on a pin 125 secured to the casing 99.

The lever 124 is moved about its fulcrum in response to movements of the yoke 25 about its trunnions 26 by a suitable compensating mechanism, so that the pilot valve will be restored to neutral when the yoke has reached a position corresponding to the position of the hand lever 114. As shown in Fig. 2, a lever 127 is secured at one end to a fulcrum pin 128 which is rotatably mounted in the casing 99 directly above and in alignment with the upper trunnion 26. The other end of the lever 127 is connected to the yoke 25 by means of a stud 129. A pin 131 projects upwardly from the lever 127 intermediate its length, and this pin is straddled by a fork 132 on the adjacent end of the lever 124. Preferably a pointer 134 is secured to the upper end of the fulcrum pin 128 to travel over a scale 135 (Fig. 10) and thereby indicate the position of the yoke 25.

The operation of the invention will now be apparent from the above disclosure. The shaft 21 will be rotated in the direction of the arrow in Fig. 3 by any suitable source of power. The geared pump 63 will draw oil from the reservoir 16 through the pipe 73 and supply this oil at a substantially uniform pressure of say 100 lbs. per square inch to the pipes 75 and 104, the excess oil flowing from the outlet chamber 68 (Fig. 6) back to the inlet chamber 68 past the relief valve 71. With the hand lever 114 in its neutral position and the two rotors 17 and 22 aligned, there will be no flow through the pipes 53 and 54, and the hydraulic motor connected therewith will be stationary. If the operator wishes this motor to operate in a forward direction, he will turn the

hand lever 114 in a counter-clockwise direction as viewed in Fig. 10, which will swing the floating lever 121 about its fulcrum on the link 123 and slide the pilot valve 109 to the left, allowing oil under pressure to flow from the pipe 104 through the chambers 102 and 100 to the pipe 105 and the cylinders 93. The pistons 95 in Fig. 4 will move to the right, causing the yoke 25 and the pistons 96 to also move to the right. Oil will exhaust from the cylinders 94 through the pipe 106 and chamber 101 to the interior of the casing 15. This movement of the yoke 25 about its trunnions 26 will swing the lever 127 (Fig. 2), which in turn will actuate the lever 124 and link 123 in the proper direction to return the pilot valve 109 to its neutral position. When this occurs, the yoke will come to rest, having moved the pointer 134 over the scale 135 to a position corresponding with that indicated on the scale 117 by the pointer 116. Because of the angular relationship which now exists between the axes of the two rotors 17 and 22, the pistons 34 and the cylinders 33 will have relative reciprocating movements. This will cause oil to be drawn into the cylinders 33 through the pipe 53 and chamber 51, and delivered from the cylinders through the chamber 52 and pipe 54 to the hydraulic motor to operate the same in a forward direction. The pressure of this delivered oil will hold the check valve 85 (Fig. 5) closed and the check valve 84 open. Consequently, oil from the geared pump 63 will flow past the check valve 84 and through the chamber 78 and passage 79 to the chamber 51 in sufficient quantities to make up for any internal leakage from the main pump and also ensure complete filling of the main pump cylinders at each stroke. If the pressure in the delivery chamber 52 of the main pump should become excessive, the relief valve 90 will open automatically to allow oil to escape into the chamber 51. To reverse the hydraulic motor, the operator need merely turn the hand lever 114 in a clockwise direction to the other side of its neutral position. This will move the pilot valve 109 to the right in Fig. 10, admitting oil to the cylinders 94, and moving the yoke 25 to the other side of its central position. The pilot valve will automatically return to neutral position when the yoke has reached a position corresponding to the new position of the hand lever. The oil will now be drawn into the main pump from the pipe 54 and discharged from the main pump into the pipe 53, reversing the hydraulic motor. Make-up oil from the geared pump will enter the chamber 52 past the check valve 85, which will now be open. The relief valve 89 will afford protection against excessive oil pressure in the chamber 51. It will be understood that regardless of the direction of oil flow, the volume of the oil flow and the resultant speed of the hydraulic motor will be dependent upon the size of the angle between the axes of the two rotors 17 and 22, as determined by the angle through which the hand lever 114 is moved from its neutral position. The pointer 134 will indicate to the operator the position of the yoke 25, and if the various parts are functioning properly this position will always correspond to that of the pointer 116.

From the above disclosure, it will be apparent that the invention provides a highly efficient multiple cylinder pump which will be comparatively free from friction and wear, relatively simple and inexpensive to manufacture, and thoroughly dependable in service. The direction of fluid flow can be readily reversed, and make-up fluid will

be supplied to the pump inlet automatically regardless of such reversal. The pump is also protected against excessive discharge pressures for either direction of flow. The pump can be reversed and its capacity readily varied by the simple adjustment of a single hand-lever.

This is a continuation in part of my application No. 456,523 filed August 28, 1942, and abandoned July 31, 1943.

Having thus described my invention, what I claim as new and desire to secure by Letters Patent is:

1. A fluid pump comprising a casing, a main rotor rotatably supported in the casing, a yoke pivotally mounted in the casing, an auxiliary rotor rotatably supported in the yoke, means connecting the rotors for simultaneous rotation in the same direction, an annular series of fluid displacement units located between the rotors and each including a cylinder and a piston, means providing ball-and-socket joints between the opposite ends of each unit and the respective rotors, means to admit fluid to the cylinders as the units lengthen and to withdraw fluid from the cylinders as the units contract, a hydraulic motor connected to the yoke to move the same about its pivot, a pilot valve arranged to control the flow of fluid to the motor and having a neutral position, a control device for the pilot valve, and compensating mechanism connecting the yoke with the pilot valve to return the same to its neutral position as the yoke reaches a position corresponding to the position of the control device.
2. A fluid pump comprising a casing, a main rotor rotatably supported in the casing, a yoke pivotally mounted in the casing, an auxiliary rotor rotatably supported in the yoke, means connecting the rotors for simultaneous rotation in the same direction, an annular series of fluid displacement units located between the rotors and each including a cylinder and a piston, means providing ball-and-socket joints between the opposite ends of each unit and the respective rotors, means to admit fluid to the cylinders as the units lengthen and to withdraw fluid from the cylinders as the units contract, a hydraulic motor connected to the yoke to move the same about its pivot, a pilot valve arranged to control the flow of fluid to the motor and having a neutral position, a lever connected to the pilot valve, a movable fulcrum for the lever, a control device for the pilot valve connected to the lever, and compensating mechanism connecting the yoke with the lever fulcrum to move the same and return the pilot valve to its neutral position as the yoke reaches a position corresponding to the position of the control device.
3. A fluid pump comprising a casing, a main rotor rotatably supported in the casing, a yoke pivotally mounted in the casing, an auxiliary rotor rotatably supported in the yoke, means connecting the rotors for simultaneous rotation in the same direction, an annular series of fluid displacement units located between the rotors and each including a cylinder and a piston, means providing ball-and-socket joints between the opposite ends of each unit and the respective rotors, means to admit fluid to the cylinders as the units lengthen and to withdraw fluid from the cylinders as the units contract, a hydraulic motor connected to the yoke to move the same about its pivot, means indicating the position of the yoke, a pilot valve arranged to control the flow of fluid to the motor and having a neutral posi-

tion, a control device for the pilot valve, means indicating the position of the control device, and compensating mechanism connecting the yoke with the pilot valve to return the same to its neutral position as the yoke reaches a position corresponding to the position of the control device.

4. A fluid pump comprising a casing, a main rotor rotatably supported in the casing, a yoke pivotally mounted in the casing, an auxiliary rotor rotatably supported in the yoke, means connecting the rotors for simultaneous rotation in the same direction, an annular series of fluid displacement units located between the rotors and each including a cylinder and a piston, means providing ball-and-socket joints between the opposite ends of each unit and the respective rotors, means to admit fluid to the cylinders as the units lengthen and to withdraw fluid from the cylinders as the units contract, two cylinders mounted on the casing on opposite sides thereof with their inner ends open into the casing, a single-acting piston slidably mounted within each of the said two cylinders, connecting rods joining the single-acting pistons with the yoke, a pilot valve arranged to control the flow of fluid to and from the said two cylinders and having a neutral position, a control device for the pilot valve, and compensating mechanism connecting the yoke with the pilot valve to return the same to its neutral position as the yoke reaches a position corresponding to the position of the control device.

5. A fluid pump comprising a casing, a main rotor rotatably supported in the casing, a yoke pivotally mounted in the casing, an auxiliary rotor rotatably supported in the yoke, means connecting the rotors for simultaneous rotation in the same direction, an annular series of fluid displacement units located between the rotors and each including a cylinder and a piston, means providing ball-and-socket joints between the opposite ends of each unit and the respective rotors, means to admit fluid to the cylinders as the units lengthen and to withdraw fluid from the cylinders as the units contract, two pairs of cylinders mounted on the casing on opposite sides thereof with their inner ends open into the casing, a single-acting piston slidably mounted within each of the last-mentioned cylinders, connecting rods joining the single-acting pistons with the yoke, a pilot valve arranged to control the flow of fluid to and from the said pairs of cylinders and having a neutral position, a control device for the pilot valve, and compensating mechanism connecting the yoke with the pilot valve to return the same to its neutral position as the yoke reaches a position corresponding to the position of the control device.

6. A fluid pump comprising a casing, a series of fluid displacement units located within the casing and each including a cylinder and a piston, a drive shaft rotatably mounted in the casing, means connecting the drive shaft with the

said units to actuate the same, two chambers each of which is adapted to serve as an inlet chamber while the other serves as an outlet chamber, means to connect each of the said units with the said chambers alternately, means to reverse the fluid flow through the pump during the continuous rotation of the shaft in one direction, means providing an intermediate chamber, a make-up pump driven from the shaft and arranged to deliver pressure fluid to the said intermediate chamber, separate passages connecting the intermediate chamber with each of the said two chambers, and a check valve in each passage arranged to open in the direction of flow out of the intermediate chamber.

7. A fluid pump comprising a casing, a series of fluid displacement units located within the casing and each including a cylinder and a piston, a drive shaft rotatably mounted in the casing, means connecting the drive shaft with the said units to actuate the same, two chambers each of which is adapted to serve as an inlet chamber while the other serves as an outlet chamber, means to connect each of the said units with the said chambers alternately, means to reverse the fluid flow through the pump during the continuous rotation of the shaft in one direction, means providing an intermediate chamber, a make-up pump driven from the shaft and arranged to deliver pressure fluid to the said intermediate chamber, separate passages connecting the intermediate chamber with each of the said two chambers, a check valve in each passage arranged to open in the direction of flow out of the intermediate chamber, and means effective, when either of the check valves is closed, to open the other check valve.

8. A fluid pump comprising a casing, a series of fluid displacement units located within the casing and each including a cylinder and a piston, a drive shaft rotatably mounted in the casing, means connecting the drive shaft with the said units to actuate the same, two chambers each of which is adapted to serve as an inlet chamber while the other serves as an outlet chamber, means to connect each of the said units with the said chambers alternately, means to reverse the fluid flow through the pump during the continuous rotation of the shaft in one direction, means providing an intermediate chamber, a make-up pump driven from the shaft and arranged to deliver pressure fluid to the said intermediate chamber, separate passages connecting the intermediate chamber with each of the said two chambers, a check valve in each passage arranged to open in the direction of flow out of the intermediate chamber, and two spring-loaded relief valves to control flow of fluid between the said two chambers and opening in opposite directions of flow.

PAUL C. TEMPLE.
